UNITED STATES PATENT OFFICE.

LOWELL CASE, OF HERKIMER, NEW YORK.

SHOOTING-GALLERY.

1,294,618.

Specification of Letters Patent. Patented Feb. 18, 1919.

Application filed May 8, 1918. Serial No. 233,296.

To all whom it may concern:

Be it known that I, LOWELL CASE, a citizen of the United States, residing at Herkimer, in the county of Herkimer and State of New York, have invented certain new and useful Improvements in Shooting-Galleries, of which the following is a specification.

This invention relates to games, and more especially to game apparatus involving an aerial projectile; and the object of the same is to produce a game of this kind including a manually operated gun in the nature of a catapult, and a target for the same which is set by the same impulse which sets the gun.

Another and a patriotic object of the invention is carried out by designing a part of the gun in imitation of a United States artillery man and a part of the target in simulation of his worst enemy.

Other objects will appear in the following specification and claims, and attention is invited to the accompanying drawings, wherein:—

Figure 1 is a side elevation partly broken away and partly in section,

Fig. 2 is a horizontal section on the line 2—2 of Fig. 1,

Fig. 3 is a vertical section on the line 3—3 of Fig. 1,

Fig. 4 is a rear elevation of the target, Fig. 5 is a sectional detail on the line 5—5 of Fig. 1.

For economy in transportation and storage, this device is preferably made in three main parts detachably connected with each other. The numeral 1 designates a base upon which at 2 is screwed the foot 3 of the target structure, and upon which base also at 4 is screwed the foot 5 of the gun structure, these two objects being supported by the base which will of course be of any suitable length, and may even have feet of its own.

The gun comprises a pair of upright standards 10 rising from the foot 5 and spaced from each other by blocks 11, a tubular element or barrel 12 carried upon the standards by a clip 13, a breech block or firing pin 14 slidably mounted in the rear end of the gun as best seen in Fig. 2, and a hammer consisting of a figure in imitation of an artillery man as at 15, a block or weight 16 adapted

to strike the firing pin, and a pivot 17 by which the figure is mounted between the standards 10. The numeral 18 designates the projectile herein shown as a small rod or dart connected with some fixed point by a chain or cord 19 so that it will not become lost or misplaced. A spring 20 is connected at 21 with the figure 15, its body extending between the standards as seen at Fig. 5, and its front end has a pin 22 for adjustable engagement with one of a row of notches 23 formed in the forwardly inclined front edges of the standards as seen in Fig. 1. Obviously by adjusting this pin to the different notches, the tension of the spring may be increased or decreased. The rear lower end of the figure is curved downward into what I will call a heel 25 which is adapted to contact with the short arm of a lever 26 pivoted at 27 between the standards, with its long arm overlying and extending the full length of the base 1 as shown.

The target element comprising an upright 30 having guides 31 along its rear at its 75 edges in which slides a block 32 notched at its lower ends as at 33 for reception of the tip of the lever 26, the latter moving through a slot 36 in the upright as seen in Figs. 1 and 3. Hinged at 34 to the upper edge of the 20 block 32 is a figure 35 which constitutes the target proper, and when the movable parts are raised this figure is visible through an opening 37 in the upright, the axial center of this opening being in direct line with the 35 bore of the barrel 12 as indicated by the dotted line in Fig. 1. A cross bar 38 connects the guides 31 so that when the figure falls to the rear as shown in dotted lines in Fig. 1 it will rest on said cross bar and be out 90 of sight through the opening 37.

The operation of so much of my invention as has been described is as follows:—The player puts his finger on the upper end of the figure 15 and draws it back about to the 95 position shown in dotted lines in Fig. 1, the heel 25 thereof depressing the short arm of the lever. This causes its long arm to raise the block and the figure 35, so that the latter comes into sight through the opening 37. Now the operator quickly releases the hammer 15, with the result that the spring causes

it to move forward and the weight 16 strikes the firing pin 14 which latter in turn projects the dart 18 along the dotted line in this view. If the spring has been set at proper tension, and if the player of this game is sufficiently dexterous, he may cause the projectile to hit the face of the figure. The figure will fall over to the rear as indicated in dotted lines in Fig. 1 and rest on the cross bar 38, and the projectile can be placed in the gun for the next shot. To reset the target element, it is only necessary to press downward on the lower arm of the lever, which draws the block 32 downward and causes the hinge 34 to travel past the cross bar 38, with the result that the figure 35 is raised and the parts resume the position shown in Fig. 4.

Another feature which may be adopted in connection with this device and which I preferably employ, is a flag 40 mounted on a rod 41 and pivoted at 42 to the side of the upright 30, its short arm 43 having a finger 44 standing in rear of the device and positioned to be hit by the figure 35 when it falls over to the dotted lined position of Fig. 1. Thus a good shot which hits the target squarely, knocks the figure over the rear, and sets up a white flag, which is doubtless typical of just what the player would want to have occur. When the parts are restored to their set position, the flag descends ready for renewed operation at the next successful shot.

The foregoing description and the drawings have reference to what may be considered the preferred, or approved form of my invention. It is to be understood that I may make such changes in construction, and arrangement and combination of parts, materials, dimensions, et cetera, as may prove expedient and fall within the scope of the appended claims.

Having thus fully described my invention, what I claim as new and desire to secure by Letters Patent, is:—

1. In a toy shooting gallery, the combination with the gun element and its projectile; of a target element comprising a slotted upright, the target proper movably mounted thereon, and a lever pivoted between its ends with its long arm engaging said target and its short arm depressed by the setting of the gun.

2. In a toy shooting gallery, the combination with a base, a target element upstanding therefrom and containing a movable target proper, and a lever pivoted between its ends with one arm engaging the target proper; of a gun element mounted on said base and comprising a pair of spaced standards supporting a barrel, a firing pin therein, a hammer pivoted between said standards and having a weight in line with

the firing pin, the hammer having a heel 65 adapted to depress the short arm of said lever, and a spring for moving the hammer forward.

3. In a toy shooting gallery, the combination with a base, a target element upstanding therefrom and containing a movable target proper, and a lever pivoted between its ends with one arm engaging the target proper; of a gun element mounted on said base and comprising a pair of spaced 75 standards supporting a barrel, a firing pin therein, a hammer pivoted between said standards and having a weight in line with the firing pin, the hammer having a heel adapted to depress the short arm of said 80 lever, a spring connected at its rear end with said hammer and extending between said standards, the latter having an inclined row of notches along their front edges, and a pin at the front end of said spring adjustably mounted in certain of said notches, for the purpose set forth.

4. In a toy shooting gallery, the combination with a base, a gun element at one end thereof, and a lever pivoted between 90 its ends upon said base and having a short arm underlying the gun element and depressed when the hammer thereof is retracted; of an upright rising from the other end of said base and having a slot in which 95 the long arm of said lever projects and an opening at the upper end of the slot, guides on the rear of said upright, a block movably mounted in said guides and engaged by the long arm of said lever, and a target 100 proper carried by said block and adapted to be exposed through said opening when the block is raised.

5. In a toy shooting gallery, the combination with a base, a gun element at one end 105 thereof, and a lever pivoted between its ends upon said base and having a short arm underlying the gun element and depressed when the hammer thereof is retracted; of an upright rising from the other 110 end of said base and having a slot in which the long arm of said lever projects and an opening at the upper end of the slot, guides on the rear of said upright, a block movably mounted in said guides and engaged by the long arm of said lever; a figure-target hinged to the upper edge of said block and exposed through said opening when the block is raised, and a cross bar connecting said guides and over which the 115 figure falls when struck by the projectile from the gun.

6. In a toy of the type described, the combination with a gun element and its projectile, an upright having vertical guides, 120 a block movable therein, and a target figure hinged to said block; of a bar connecting the guides in rear of the upright and upon

which said figure falls when it is struck, and a flag mounted on a bent rod hinged at its angle to one edge of said upright with its short arm having a finger standing 5 in rear of the same and adapted to be struck by said figure, as described.

In testimony whereof I affix my signature in presence of two witnesses.
